DESIGN FOR A BURIAL VAULT

Harry Cohen, Galion, Ohio, assignor to The Perfection Steel Body Company, Galion, Ohio,
a Corporation

Application June 5, 1933. Serial No. 48,277

Term of patent 14 years

To all whom it may concern:

Be it known that I, HARRY COHEN, a citizen of the United States, residing at Galion, in the county of Crawford and State of Ohio, have invented a new, original, and ornamental Design for Burial Vaults, of which the following is a specification, reference being had to the accompanying drawing, forming a part thereof, in which—

The figure is a perspective view of a burial vault showing my new design.

I claim—

The ornamental design for a burial vault, substantially as shown.
